UNITED STATES PATENT OFFICE

90,959

DESIGN FOR A BURIAL CLOISTER BUILDING

Ulysses J. Smith, Cleveland, Ohio

Application August 31, 1933. Serial No. 49,179

Term of patent 7 years

To all whom it may concern:

Be it known that I, ULYSSES J. SMITH, a citizen of the United States, residing at Cleveland, in the county of Cuyahoga and State of Ohio, have invented a new, original, and ornamental Design for a Burial Cloister Building, of which the following is a specification, reference being had to the accompanying drawing, forming part thereof.

Figure 1 is a perspective view of the burial cloister building, showing my design, the rear wall faces being flat;

Figure 2 is a top plan view thereof.

I claim:—

The ornamental design for a burial cloister building, as shown and described.

ULYSSES J. SMITH.
